CLAIM

The ornamental design for a hair dryer, as shown and described.

DESCRIPTION

FIG. 1 is a front perspective view of a hair dryer, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion "9" shown in FIG. 1;

FIG. 10 is an enlarged view of portion "10" shown in FIG. 1;

FIG. 11 is an enlarged view of portion "11" shown in FIG. 1;

FIG. 12 is an enlarged view of portion "12" shown in FIG. 2;

FIG. 13 is an enlarged view of portion "13" shown in FIG. 2;

FIG. 14 is an enlarged view of portion "14" shown in FIG. 3;

FIG. 15 is an enlarged view of portion "15" shown in FIG. 8; and,

FIG. 16 is an enlarged view of portion "16" shown in FIG. 8.

The dashed broken lines in the figures are for the purposes of illustrating portions of the hair dryer that form no part of the claimed design.

The dash-dot-dash broken lines are for notating enlarged views and form no part of the claimed design.
